UNITED STATES PATENT OFFICE.

HENRY SCHWESINGER, OF DETROIT, MICHIGAN.

PNEUMATIC PIANO-PLAYER

No. 895,803.

Specification of Letters Patent. Patented Aug. 11, 1908.

Application filed May 9, 1902. Serial No. 106,575.

To all whom it may concern:

Be it known that I, HENRY SCHWESINGER, a citizen of the United States, residing at Detroit, county of Wayne, State of Michigan, have invented a certain new and useful Improvement in Pneumatic Piano-Players, and declare the following to be a full, clear, and exact description of the same, such as will enable others skilled in the art to which it pertains to make and use the same, reference being had to the accompanying drawings, which form a part of this specification.

This invention relates to pneumatic piano players, and has for its object an improvement in that class of pneumatic instruments in which provision is made for employing a perforated sheet of paper as a valve, which allows the passage of a current of air at times, and the current of air that passes through the perforations in the paper actuates valves which regulate the direction of movement of another current of air, and this second current of air, is arranged to actuate motors, and either directly or indirectly actuate hammers which strike upon keys of the piano to cause them to produce musical notes.

In embodying the invention, I employ the perforated music paper as a valve, and I employ an air driven motor which serves to draw the sheet of perforated paper over a tracker board, through which there are holes or passages. The perforations in the music sheet register at times with these holes, and at such times the perforated music sheet allows the free movement of air through the passage in the tracker board, and allows the flow therethrough of a current of air which sets the valves in a system of passages and chambers, through which there is another movement of air, the direction of which is regulated by the valves thus set.

I employ the chamber in which the music sheet is located as an air trunk, and I shall refer to it hereinafter as an air trunk, although it contains the music sheet and mechanism for winding and rewinding the music sheet.

I employ a pair of bellows which are actuated by the feet of the operator or some other adequate power; one of these bellows is arranged to produce a forced blast of air and the other is arranged as an exhaust bellows.

The air traverses several chambers and passages and by its movement actuates a motor

which shifts a perforated music sheet over a tracker board; the music sheet acts as valves to control the movement of air through the several openings through the tracker board and air passing through these openings actuates a primary pneumatic, and a valve that is connected therewith and this valve controls the direction of movement of the air put in circulation by the blast and exhaust above referred to, and this circulating air is directed in movement through the several chambers and passages contained in an air trunk and actuates a hammer motor connected with said air trunk. In the air trunk which contains the hammer motor is a movable hollow stemmed structure of which several parts act as independent valves engaging with the independent valve seats, and this movable part in the various positions which it assumes, controls the direction of the air movement from one chamber to another in this air trunk; the motive air which enters this trunk like that which enters the trunk which contains the tracker board, enters through a passage which leads from the blast bellows and leaves it through a passage which leads to the exhaust bellows. In connection with every one of the minor motors, which are employed in the device, there is provision made to urge its motion in one direction by air coming from the forcing bellows and to urge its motion in the same direction by drawing or exhausting air that would otherwise serve to obstruct its free motion; the valves which have been spoken of as being set, are arranged to change the direction by which the air moves through the chamber and passages, so that when the valve is set in one position, the current of air moving through the instrument tends on the one side to push, and on the other to draw the minor motor, and when the valves are set in another position, the current of air still tends to push in one direction and to draw in the same direction, but the direction of movement of the motor is changed.

In connection with the motor which actuates the music sheet, I have made provision for regulating the flow of air, by placing in one of the passages through which the air, which actuates this part of the machine, travels, an automatic regulator which chokes down if the current becomes too strong, and opens out if the current becomes too weak.

Another feature of improvement relates to

the forward feed of the paper roll, and the means for shifting therefrom for a return feed for rewinding the paper roll.

Other features of improvement will be described and claimed.

In the drawings:—Figure 1, is a cross section through the instrument showing the chambers, passage-ways and valves, and showing in elevation some of the parts which actuate the music roll. Fig. 2, is a longitudinal section showing an end of the music roll and the means for shifting from forward to back feed.

In Fig. 1, the bellows part actuated by the feet is largely reduced in proportion to the upper part of the drawing, and in the upper part of the drawing there are shown above the key hammer K, an actuator with the valves with the several parts thereof in the position occupied when the music sheet is arranged to close the openings through the tracker board. In the lower part a similar arrangement of chambers, passage-ways, and valves is shown, with the several parts in the position they occupy when the music sheet is in position to allow the air to pass through the tracker board. In a complete machine there are a large number of devices, duplicates of the two that are shown, arranged in two tiers as indicated in the drawings.

The actuating current of air is produced by the treadles 1 and 2, of which the treadle 1, produces blast current by actuating bellows 35, forcing air into chamber 4, and thence through conduit 5 to the motor which actuates the piano hammer, and through conduit 6 into the air trunk 7, in which the perforated music sheet is placed. The treadle 2 actuates the bellows 36 and exhausts air from the chamber 8, drawing it through conduit 9 from that part of the device which actuates the piano hammer, and through conduit 10 through a regulating device from the motor which actuates the paper roll. This motor is located at one end of the trunk 7, in which the music sheet is arranged. Blast air passes through the conduit 6 into the air trunk 7 and thence through the perforations in the sheet of paper, as the paper is actuated to bring the perforations therein over the passages through the tracker board 11; after passing the perforations in the paper p the air travels through the tracker board 11, through the conduit 12, into that part of the apparatus which contains the hammer actuating device, where the blast air arriving from the tracker board actuates a primary bellows 13, raises the movable part of it and actuates valves which admit the blast air to the hammer actuating mechanism. There are also opened passages for the exhaust air which travels from the hammer actuating part of the machine through conduit 9. The hammer actuating device consists of a compound chamber comprising individual cham-

bers 14, 16, and air passages 15, 17 and 18. The air from conduit 5 presses into chamber 16; and chamber 14 exhausts into conduit 9. The air from conduit 12 presses into primary bellows 13, the lower face of which is secured to the framework or wall 19 of the chamber and the upper part of which is held thereto by bellows connection, and under the force of the air this upper part rises, lifts the stem 20 of a valve 21, that rests over an opening 22, in a vertically movable valve chamber 23. The valve chamber is itself a valve adapted to close an annular aperture 24 through the wall 25 above chamber 14. Through the aperture 24, there is communication between chamber 14 and passage 15, and the aperture is closed by the casing of chamber 23, which acts as a valve to close it when lifted. The primary bellows first lifts the valve 21, which engages against struts 26 that project into the chamber 23, it next lifts the casing of chamber 23, and the hollow stem 27 until the passage 24 is closed. The struts 26 hold the valve 21 off from the entrance to the hollow stem 27, and there is now an open passage 90 for air through the hollow stem 27, which allows communication between passage 18 and chamber 14. The upper end of the hollow stem 27, also forms a valve which closes against the wall 28 on a seat that surrounded an opening 29, and in its lifted position the stem closes the passage from the chamber 16, past the end of the stem 27, through the opening 29, communicating with the passage 18 and into the chamber 17. Prior to the 100 actuation of the primary 13 by air traveling through the tracker board, there was an open passage for air from chamber 16, through passage 18 into chamber 17, and the force of this air expanded the power pneumatic 30, 105 the movable board 31 of the power pneumatic was forced down to the extent of its downward throw and the hammer K was lifted and the parts occupied the position shown in the upper part of the drawing. Immediately after the actuation of the primary 13, the valve 21 lifts, and following this, the valve casing 23, and the stem 26 connected with it rise and the direction of flow through the conduit from 17 now open, is changed, so 110 that the current now exhausts into chamber 14, and from the power pneumatic 30; at the same time valve 34 is lifted opening passage-way 32, and blast current through the pipe 5 and the chamber 16 is driven through passage 15 to the under side of the movable board 31, of power pneumatic 30, and lifts the movable board co-acting with the exhaust air in this action. The lifting of the movable board lifts the link 33 and actuates 115 the hammer K.

In the actuation of the primary 13, the blast air through the tracker board and passage 12, co-acts with the force exerted by the exhaust that is drawn through conduit 9, 130

from the chamber 14. The parts are in normal position when no air has been admitted or is being admitted, through passage 12, from the tracker board, the exhaust force is holding the movable board 31 of the power pneumatic down, but at this time, notwithstanding the exhaust bellows 36, is acting as an exhaust, it cannot actuate the movable board of primary 13, because the entrance of air to the primary 13, is closed by the paper roll which now presents no opening over the tracker board; blast air, however, is at this time co-acting with the exhaust air to hold the board 31 down and it is co-acting with the exhaust air to hold the valve 21 closed on its seat; blast air is also pressing the valve 31 to its seat and co-acting with the exhaust air which tends to draw the same valve to its seat, but immediately on the admission of blast through the tracker board to actuate the comparatively large movable part of the primary 13 against the counter acting pressure on the top of smaller valve 21; the valve 21, is shifted, and immediately following this, the valve casing 23, and the valve stem 27 shifts, and the entire direction of air movement is changed.

In the roll actuator, the music is stored on roll 41, and it is transferred over the tracker board 11, to a storage roll on shaft 76. Shaft 42 is actuated by a crank and pitman 43, from a motor which consists of a three part bellows, one part of which 44 is shown in section and is shown to be actuated by exhaust air through the conduit 10, 45; conduit 45, exhausts from chamber 46, into which the air is admitted through slide valve 47 and through passages 48 and 49 which register at times with the opening to the chamber 46 and with the passage 50 from the motor bellows 44. The valve is shifted by a pitman 53, from crank shaft 42. The shaft 42 is provided with a double crank, one of which engages with the pitman 43, and through the pitman 43 is actuated from the movable board of the bellows 44, and the other crank, of less eccentricity engages, pitman 53, and actuates the valve 47. The valve 47 is a straight flat plate engaging against a wall of chamber 57 and provided with openings 48 and 49 cut through it and having a stem 54 that passes through an opening 55 in the casing of chamber 57, and the opening 55 is always closed by a sliding plate 56. The plate 47, slides on the wall of valve chamber 57, and there is an opening 58 through the wall into the chamber 57 that at times registers with the opening 49 in the plate and admits external air into the chamber 57, and thence into the motor 44 to fill the motor bellows after it has been contracted by exhausting air therefrom into chamber 8.

The link 33 which connects the power pneumatic 30 with the key K, passes through an opening 71, in the casing and provision is

made for the slight swinging motion of the rod 33, by passing the link through a washer 72, that engages over the opening 71 and under a confining cap 73 the cavity in the cap has a diameter larger than that of the washer. The washer is practically air tight between the casing and the cap, but has sufficient side motion to allow for the swinging or swaying of the rod 33, which passes through it and is capable of reciprocation.

The rewinding of the paper on the roll 41, is accomplished by the mechanism shown in Fig. 2.

The shaft 76 is provided with a gear 74, 80 that meshes with a driving pinion 75, on the shaft 77. The shaft 77, and the crank shaft 42, are coupled by a sleeve coupling, which coupling is held to slide on the shaft 42, by a short spline that engages in a long key way. 85 On the shaft 77, is a sprocket wheel 81, and on the shaft of the roll 41 is a sprocket wheel 82. There is a sprocket chain, indicated by dotted lines, passing over the wheels 81 and 82. The wheel 81 is provided with a clutch 90 hub 78; the wheel and hub may be manually actuated by a lever 79, to slide first for a short distance along the shaft 77, until the hub 78, and the coupling 80, are in clutch engagement; after which the parts including 95 the shaft 77, pinion 75, and sleeve 80, may be made to slide on the shaft 42, until the pinion 75, is out of mesh with the wheel 74; so long as the hub 78 is not in clutch engagement with the coupling 80, it rides free on the 100 shaft 77, but is doing no work; but as soon as the clutch is shifted, and the sleeve 80, is shifted to disengage the pinion 75 and wheel 74, the wheel comes into action. A spring 105 83, tends to force and hold the pinion 75, in mesh with the wheel 74. The shaft 42 and the shaft 77, always rotate in unison. Under normal conditions, this rotation drives the storing roll 85; the reverse movement is effected by shifting the shaft 77, and the 110 parts connected with it, in the way described.

What I claim is:—

1. In a pneumatic musical instrument player, in combination, an air trunk divided by partitions into a hammer motor containing chamber, a primary pneumatic containing chamber, and a chamber intermediate said hammer motor chamber and said primary pneumatic chamber, an exhaust bellows and a conduit leading thereto from said primary pneumatic chamber; a blast bellows and a conduit leading therefrom to said air trunk, a valve mechanism actuated by said primary pneumatic, having a valve to control an opening between the primary pneumatic chamber and the intermediate chamber, and a second valve to control an opening between the blast terminal and the intermediate chamber, and a third valve controlling an opening between the blast terminal 130

- and the hammer chamber, and means for actuating said valves, substantially as described.
2. In a pneumatic musical instrument player, in combination, a blast bellows, an exhaust bellows, a wind trunk divided by partitions into chambers, one of which is located at the terminal of a passage leading to the exhaust bellows, another of which is located at the terminal of a passage leading from the blast bellows, a third of which contains a hammer motor, and a fourth chamber located to communicate with the hammer motor chamber and with both of said terminal chambers, a primary pneumatic in the exhaust terminal chamber, a valve actuated by said primary pneumatic, a movable part provided with valve faces to seat on valve seats at openings between the several chambers mentioned, and to simultaneously close the passage between the blast terminal chamber and the hammer motor chamber at one side of the motor therein and open a passage between the blast terminal chamber and the hammer motor chamber at the other side of the motor therein and simultaneously open a through passage from the hammer motor chamber to the exhaust terminal chamber, substantially as described.
3. In an actuator for mechanical musical instrument players, a wind trunk divided by partitions into chambers connected by passages, one of said chambers containing a hammer actuating motor and having two admission openings thereinto for air, a second of said chambers being located at the terminal of a blast inlet pipe and communicating with the first mentioned chamber through a valve controlled opening and connected with the second inlet opening to said motor chamber through a passage and a valve controlled opening thereinto, a third chamber located at the terminal of an exhaust passage and containing a primary pneumatic, valves on a single stem for all of said openings, the said stem being hollow and having a communicating passage therethrough between the hammer motor chamber and the primary pneumatic chamber, which through-passage is itself controlled by a valve actuated by the primary pneumatic, substantially as described.
4. In a mechanical player for musical instruments, in combination with a primary pneumatic, an air controlling device connected therewith consisting of a hollow tube having a valve face at the end thereof, a collar surrounding the tube and having a valve face, an enlargement at the end of said tube, a valve seat on the inner side of said enlargement and a valve disk seating thereon, the said tube being provided opposite the valve disk with projections against which the valve disk engages whereby the passage through said movable piece may remain open and the valve disk be utilized to push against and actuate the movable piece, substantially as described.
5. In a mechanical player for musical instruments, in combination with an air trunk divided by partitions into chambers and provided with a blast pipe leading into one of said chambers and an exhaust pipe leading from another of said chambers, a movable piece provided with valve faces external thereto and hollow and provided with a valve face internal thereto and with a disk valve seating on said internal valve face, said valve faces external to the movable piece engaging alternately with seats on the several partitions, whereby air of constant direction into and out from said trunk is given alternate movements between the chambers within the air trunk, substantially as described.
6. In a mechanical player for musical instruments, in combination with an air trunk divided by partitions into chambers and provided with a blast pipe leading into one of said chambers and an exhaust pipe leading from another of said chambers, a movable piece provided with valve faces external thereto and hollow and provided with a valve face internal thereto and with a disk valve seating on said internal valve face, said valve faces external to the movable piece engaging alternately with seats on the several partitions, whereby air of constant direction into and out from said trunk is given alternate movements between the chambers within the air trunk, substantially as described.
7. In a mechanical instrument player, in combination with transfer rolls for the music sheet, a winding and rewinding means comprising a constantly moving actuator, a crank shaft actuated thereby, a driving shaft in axial alinement with said crank shaft movable along their common axis, a sleeve connection between said shafts, a pinion on said driving shaft, a gear on one of said transfer rolls with which said pinion may mesh, a sprocket wheel on said driving shaft movable longitudinal of its axis with said driving shaft, a clutch connection between said sprocket wheel and said crank shaft, a chain connection between said sprocket wheel and the second of said transfer rolls, substantially as described.
8. In a pneumatic piano player, in combination with a casing provided with suitable chambers and passages, a hollow valve stem, a valve located within the hollow stem and controlling a passage therethrough, a valve carried by said stem external thereto and adapted to close a passage through which the stem engages, a primary pneumatic engaging the valve which controls the passage through said stem and actuating the same to thereby move the stem and actuate the valves carried thereby, substantially as described.
9. In a pneumatic piano player, the com- 130

combination of a casing provided with suitable chambers and passages for the flow and reverse flow of air currents, a plurality of valves connected by a hollow stem, which is itself utilized as an air passage, a valve controlling the passage through the hollow stem, and a primary pneumatic engaging the valve which controls the passage through the stem and shifts said valve and causes said valve to shift the position of the stem and thereby

change the direction of flow of the air currents through the chambers in said casing, substantially as described.

In testimony whereof, I, sign this specification in the presence of two witnesses.

HENRY SCHWESINGER.
